ATTORNEYS.

UNITED STATES PATENT OFFICE.

CLAUDE A. LEWIS, OF HOUSTON, TEXAS, ASSIGNOR TO AMERICAN WINDOW COMPANY, OF HOUSTON, TEXAS, A CORPORATION OF DELAWARE.

SENTINEL FOR WINDOWS.

Application filed April 26, 1927. Serial No. 186,649.

My invention relates to a stop or sentinel to be used in connection with a window casing to limit the swinging movement of the window sash therein.

5 In the construction of windows in which the sash is pivoted to swing inwardly at its upper end, it is frequently desirable to limit the swinging of the sash at a certain point so as to allow a vent at the upper end thereof. Also in swinging a sash inwardly in this manner there is danger that the sash may drop from its upper closed position when it is desired to move it into a reversed position.

10 15 It is an object of my invention to provide a guard or sentinel to be used in connection with the casing so as to furnish a stop for the sash and prevent its swinging inwardly beyond a certain point. It is desired to form such a stop which will be easily releasable when desired to allow the sash to swing past the same into open position.

20 25 It is also an object to provide a stop of this kind which is simple in its construction and mounting and automatic in its operation.

30 Referring to the drawing herewith, Fig. 1 is a perspective detail of a section of window casing with my invention mounted thereon. Fig. 2 is a broken section of the upper end of the window casing showing my invention employed in connection with a swinging sash mounted in said casing. Fig. 3 is a top plan view of the invention, the casing being shown in horizontal section the sash being shown in open position engaging the sentinel as the sash is closed. Fig. 4 is a view similar to that shown in Fig. 3 with the window sash moved upwardly and the sentinel in closed position; and Fig. 5 is a side elevation of the sentinel removed from the casing.

35 40 45 My invention may be employed with any ordinary type of window in which the sash is mounted to swing on a pivot at its lower end. The drawings are therefore intended to illustrate in a more or less diagrammatic way the application of my invention to any ordinary type of window, particularly a window having a wooden casing and sash.

50 55 60 In the drawing, I have shown a section of a window casing having an upper head plate 1 with an outer face plate 2 connected therewith and extending downwardly from the head plate. There is also an inner face plate 3 extending upwardly from the head plate

and forming a facing for the window frame within the jamb. The window has the usual side plates or jambs 4 between which the sash is adapted to move.

I have shown somewhat diagrammatically 60 a sash 5 which is pivoted on pins 6 at its lower end, fitting within any desired support, such as the window jamb 4. When the said sash is erect in closed position, it is adapted to contact with the outer face plate 2 which 65 limits its movement in an outward direction. It is contemplated that the sash may be swung on its pivots 6 inwardly so as to reverse the position of the sash and expose the outer face thereof for cleaning and also to 70 provide a full ventilation at the upper end of the casing.

In connection with my casing, I have mounted a stop plate or sentinel 7. The construction of this plate may be seen particularly from Fig. 5. It has an arm 8 at one end which has an opening 9 therein to receive a pivot member 10 which, under ordinary circumstances, may be a nail or similar device in ordinary use. The forward end of 80 the guard is pointed at 11 and provides at one side thereof a cam face 12 adapted to contact with the window sash. Beyond this cam face adjacent the arm 8 is a shoulder 13 which acts as a contact member to fit against 85 the face plate 3 of the window casing, as shown in Fig. 3.

The sentinel is mounted within a slot 14 in the forward side of the window jamb. This slot is of sufficient width to receive the sentinel plate and is inclined upwardly, as shown particularly in Figs. 1 and 2. The slot or recess 14 is such as would be made by the cut of a saw in the corner of a window jamb and is of such shape as to receive 95 the triangular forward end of the sentinel. When the sentinel plate is fitted within this recess with the outer cam face 12 flush with the edge of the window jamb, as shown in Fig. 4, a nail 10 may be driven at an angle 100 transversely through the slot so as to pass through the opening 9 and form a pivot for the plate. After this has been done, the forward face plate 3 of the casing is set in position so that the shoulder 13 will fit against 105 the same when the sentinel is in open position to extend into the path of the swinging sash.

In the use of this device, the force of gravity will normally hold the sentinel plate 110

into the position shown in Fig. 1 extending directly out into the path of the sash so that when the sash swings inwardly it will contact with the sentinel and will be stopped at that point. When it is desired to release the sash from the sentinel, the operator will push upwardly on the sash and throw the sentinel plate into the recess 14 with his thumb and hold the sentinel in that position until the sash has been moved partly past the sentinel. The sash may be then swung into any desired position free of the sentinel. When the sash is again thrown into closed position, the edge of the sash will contact with the cam face 12 of the sentinel and automatically move it back into its closed position, shown in Fig. 4, and it will not therefore interfere with the closing of the sash. It will be noted that the construction of the sentinel is exceedingly simple and that it may be installed with a minimum of labor and expense. It will only be necessary to cut the recess 14 with a saw blade of the proper width and to then secure the sentinel in position with an ordinary nail. The catch is exceedingly simple in its construction and reliable and accurate in its operation.

Having thus described my invention, what I claim as new and desire to protect by Letters Patent is:

1. In a window including a casing and a sash therein pivoted at its lower end to swing inwardly, the combination of a triangular-shaped plate having an arm at one end with a pin receiving opening therein, said plate being adapted to fit within an inclined slot in said casing and to fall by gravity into open position in the path of said sash and a pivot pin extending through said opening.
2. In a window including a casing and a sash therein pivoted at its lower end to swing inwardly, the combination of a triangular-shaped plate having an arm at one end with a pin receiving opening therein, said plate being adapted to fit within an inclined slot in said casing and to fall by gravity into open position in the path of said sash and a pivot pin extending through said opening.
3. In a window including a casing and a

sash therein pivoted at its lower end to swing inwardly, the combination of a triangular-shaped plate pivotally secured within a slot in said casing, said slot being inclined upwardly so that said plate will swing by gravity into open position in the path of said sash, and means to limit the swinging of said plate.

4. In a window including a casing, and a sash pivoted therein to swing inwardly at its upper end, the combination of a stop plate pivoted at one end in an inclined position in said casing and adapted to swing by gravity into the path of said sash, said plate having a shoulder thereon adapted to engage said casing to limit the movement of said plate and retain said plate in sash supporting position.

5. In a window including a casing, and a sash pivoted therein to swing inwardly at its upper end, the combination of a stop plate pivoted at one end in an inclined position in said casing and adapted to swing by gravity into the path of said sash, said plate having a shoulder thereon adapted to engage said casing to limit the movement of said plate and retain said plate in sash supporting position, the forward side of said plate having a cam face to be engaged by said sash when it is swung upwardly, for the purpose described.

6. In a window, a casing, a sash therein pivoted to swing inwardly within said casing, and a stop plate pivoted within an upwardly inclined slot in said casing and held by gravity in an open position extending outwardly from said slot and supported by said casing in open position.

7. In a window, a casing, a sash therein pivoted to swing inwardly within said casing, and a stop plate pivoted within an upwardly inclined slot in said casing and held by gravity in an open position extending outwardly from said slot and supported by said casing in open position, said plate being free to be moved into closed position by said sash when it is swung upwardly past said plate.

In testimony whereof I hereunto affix my signature this 23rd day of April, A. D. 1927.

CLAUDE A. LEWIS.
